INVENTOR

Clarence D. Trussell,

By Attorneys,

Draser, Durk & Myers

UNITED STATES PATENT OFFICE.

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK.

LOOSE-LEAF BINDER.

1,369,309.

Specification of Letters Patent. Patented Feb. 22, 1921.

Application filed January 31, 1919. Serial No. 274,337.

To all whom it may concern:

Be it known that I, CLARENCE D. TRUSSELL, a citizen of the United States of America, residing in Poughkeepsie, in the county of Dutchess and State of New York, have invented certain new and useful Improvements in Loose-Leaf Binders, of which the following is a specification.

This invention relates to temporary binders or those designed for binding together loose leaves in book form. It relates particularly to so-called ring binders, wherein half rings or hooks are adapted to close together to constitute binding means and to open out to permit the removal of the perforated sheets or leaves.

The invention provides improved means for the attachment of the binding elements to the book back.

20 In the accompanying drawings,—

Figure 1 is a fragmentary view showing the book cover in an incomplete state;

Fig. 2 shows it in a later stage of manufacture;

25 Fig. 3 is a transverse section on the line 3—3 in Fig. 1, on an enlarged scale;

Fig. 4 is a similar section on the line 4—4 in Fig. 2, including the binding devices;

30 Fig. 5 is a longitudinal section on the line 5—5 in Figs. 2 and 4.

In the figures, A designates the book cover, of which B is the back and C C are the sides; D, as a whole, is the loose-leaf binding mechanism, shown completely only in Figs. 4 and 5; E E are the hooks or half rings of such mechanism, F F are its hook plates carrying such hooks, G is the back plate carrying the hook plates, and H is the binding plate attached to the book back, 40 whereby to attach the binding mechanism to the book cover. All of these parts may be of the usual or any known construction, except in so far as concerns the present invention in the respects hereinafter set forth.

45 Commonly, the binding plate H is fastened to the back B, and, being made of metal, has ears I on its ends, which, when the binding mechanism D is applied, are turned inwardly and downwardly, as shown in Figs.

50 4 and 5, so as to bind or clamp the plate G at its opposite ends. The plates J J shown in Fig. 5, are merely finishing plates for covering up the mechanism, particularly at its exposed ends, and form no part of the present invention.

In the construction shown, the book cover A is integral being made preferably of a single piece or thickness of leather (or other suitable material) so as to form both the back B and the sides C C. Preferably this single layer of leather is formed with grooves at K K coinciding approximately with the junction of the back and sides, so as to form a weakened line or integral hinge joint; or such grooves may be omitted, as shown in Fig. 4. When a superior finish is desired on the inside of the cover, a thin fabric lining L may be applied by pasting or cementing to the leather cover, or this may be omitted.

Some difficulty has been encountered in the manufacture of ring books of this general character in providing a suitable attachment for the ring-binding mechanism to the book back; and various constructions have been devised for accomplishing this end. According to the present invention,

75 the binding plate H, which is best made as a curved plate of metal, is secured to the back B by means of a strip M of suitable fabric which is united to the back by two rows of stitching a a, as heretofore.

To make such rows of stitching secure, it is necessary that the end portions a' (Fig. 1) of the threads

80 shall be securely attached so that the stitching may not pull out. Heretofore this has

been done by drawing through the threads to the interior and tying them in knots, which involves the tedious tying of four knots to each cover. Heretofore the side flaps of the fabric M beyond the stitching 85

have extended outwardly and been left loose, or have been confined under a lining layer.

According to my present invention, I draw 90 all the terminal threads a' inward, as shown in Fig. 1, preferably fastening them down temporarily with a dab of paste. I then

apply a sheet N of gutta percha (or other slightly fusible cementitious gum, or fabric coated with such cementitious gum) cut to 95

fit accurately between the rows a a of stitching, and of the length of the binding strip M, and press it into place against the binding strip between the stitching. The two

100 wings or flaps of the binding strip M are then turned inward and folded down upon the strip of gutta percha, and by means of a heated iron or tool of suitable shape, heat

105 is applied to soften the gutta percha and render it slightly plastic and adhesive,

110

whereby it is securely cemented to the back of the binding strip, and the flaps of the strip are cemented down upon the gutta percha, and at the same time the end portions α' of the stitching threads are also securely cemented in. The side flaps of the binding strip M may be cut to such width that they meet neatly edge to edge, as shown in Figs. 2 and 4, or they may be cut to less width, so that they leave a portion of the gutta percha strip exposed. The binding plate H is inserted in the pocket formed by stitching on the strip M. These operations being completed, the cover is in the condition shown in Fig. 2, with the ends of the plate H slightly protruding and its ears I I outturned. The ring structure D is then applied and the ears I I clenched down upon it, as shown in Fig. 5. Finally, the ornamental cover plates J J may be put in place if desired.

The construction thus described has important practical advantages, making a very neat and strong attachment, and one which minimizes hand labor and reduces expense. It is applicable not merely to the one-ply construction (or one ply with lining) described, but also with any construction of cover, whether flexible or rigid, or whether made of one, two, or more plies.

The invention may be modified or varied in certain respects within the scope of the claims. The construction for attaching the ring-binding mechanism admits of application with a wide variety of such mechanisms,

many different constructions of which are known in the art.

I claim as my invention:

1. A loose-leaf binder comprising a cover and a binding mechanism, having a back plate, and uniting means comprising a binding strip fastened to the cover along two parallel lines, and with its outer flaps turned in against its inner portion.

2. A loose-leaf binder comprising a cover and a binding mechanism, having a back plate, and uniting means comprising a binding strip united to the cover back by two parallel rows of stitching, the terminal threads thereof turned inwardly, and with the outer flaps of said strip turned in against its inner portion and confining said terminal threads.

3. A binder according to claim 1, with a strip of cementing material applied against the inner portion of the binding strip and between such portion and the turned-in flaps thereof.

4. A binder according to claim 1, with a metal binding plate confined between the binding strip and book back, and ears thereon adapted to be turned inwardly and clenched down to confine the back plate of the binding mechanism, whereby the in-turned flaps of the binding strip are confined between said plates.

In witness whereof, I have hereunto signed my name.

CLARENCE D. TRUSSELL.
